FIRE ALARM

James W. Herman and George M. Ohmann,
Albertville, Minn.

Application March 21, 1939, Serial No. 263,233

1 Claim. (Cl. 200—140)

This invention appertains to new and useful improvements in fire alarms and more particularly to an alarm which will be quick acting and substantially fool-proof.

5 The principal object of the present invention is to provide a fire alarm mechanism in which heat responsive units are provided and constructed in such a manner that they will not automatically operate to energize the alarm unless there 10 is the presence of sufficiently high temperature.

Other objects and advantages of the invention will become apparent to the reader of the following specification.

In the drawings:

15 Figure 1 represents a side elevational view of the circuit closing means mounted within a cage.

Figure 2 is a side elevational view (enlarged) of the circuit closing means partly in section.

Figure 3 is a vertical sectional view through 20 the circuit closing unit.

Figure 4 is a diagrammatic view disclosing the electrical connections between the electrical devices involved.

25 Referring to the drawings wherein like numerals designate like parts, it can be seen that the circuit closing unit consists of the base 5 upon which is mounted the mesh cage 6 within the confines of which is located the circuit closing unit 7. This unit consists of the U-shaped frame 8 through one leg portion of which is disposed the bushing 9 of insulation. Feedable through this bushing of insulation is the contact screw 10. A second contact screw 11 is feedable directly through the leg last-mentioned and 30 above the screw 10.

35 A bushing of insulation 12 is disposed through the other leg of the frame 8 and a screw 13 is disposed through this bushing 12 to support the two wafers 14, from one of which extends the neck 15 to support the hollow head 16.

40 On the hollow head 16 is secured the block 17 of insulation and into this block 17 extends the conductor 18 which is secured in place by the contact screw 19, the latter being located in opposed relation to the contact screw 10. A conductor 20 is secured to the screw 13 by the jam nut 21. Jam nuts 22 on the contact screw 10 serve to secure the conductor 23 in place.

45 As can be seen in Figure 4, numeral 25 represents the source of current from which the lead 26 extends and connects to each of the frame 8 by jumpers 27. This lead also extends to connect the lamps 28 in the lamp box 29 and each 50 of these lamps is designated as to its location by suitable numeral covered windows or the like.

The bulbs 28 are thus connected in multiple with the contact screws 10. The wires 18 from the contacts 19 extend to the return side of the battery and the conductors 20 extend to the siren 30 which has its return side extending by way 5 of the conductor 31 to the negative side of the battery 25.

In the operation of the apparatus it can be seen that the screws 10 and 11 are so adjusted through the bracket 8 that the contact 19 will first engage the screw 10, after which further expansion of the wafers 14 will flex the head 16 so that the head 16 will engage the screw 11. When the contact 19 engages the screw 10, current will flow from the battery 25 through one of the jumpers 15 18 to the contact 19 and from the contact 19 to the screw 10 and from the screw 10 to the corresponding lamp 28. The lamps 28 have a common return to the negative side of the battery 25, and this negative side is also connected by 20 the jumpers 21 to the frame 8 by means of a binding screw 8a. Thus it can be seen, that when the head 16 is flexed by further expansion of the wafers 14, after the contact 19 has engaged the screw 10, the head 16 in engaging the screw 11 25 will establish a connection through the siren 30. In other words, current will pass along the conductor 31 to the siren 30 and from there to the binding post 13, through the wafers 14 and head 16 to the screw 11, and from there to the bracket 30 8 and back to the negative side of the battery 25 by way of the conductor 26. Thus the siren will be sounded subsequent to indication of a high temperature by one of the lamps 28.

35 While the foregoing specification sets forth the invention in specific terms, it is to be understood that numerous changes in the shape, size and materials may be resorted to without departing from the spirit and scope of the invention as 40 claimed hereinafter.

Having described the invention, what is claimed as new is:

45 A switch of the character described comprising a U-shaped frame, an expansible thermostatic element, said frame being of current conducting material, said expansible thermostatic element being of current conductive material and provided with a yieldable head at one side thereof, a contact carried by the head and insulated therefrom, a set screw, a bushing of insulation in one end of the frame through which the screw is adjustable with one end normally in spaced relation with the contact, a second screw directly feedable through the frame end adjacent the 50 55

first-mentioned screw and adapted to be engaged by the head only after the contact has engaged the first mentioned screw and the head has yielded as the result of further expansion of the thermostatic element, said frame at its opposite end being provided with a bushing of insu-

lation and a binding post and securing means disposed through the last-mentioned end of the frame to support the expansible thermostatic element.

JAMES W. HERMAN.
GEORGE M. OHMANN.
